UNITED STATES PATENT OFFICE

JOSEPH PETER EASTMAN, OF MANITOWOC, WISCONSIN

CONTACT FOR ELECTRICAL HEATER PLUGS

Application filed March 14, 1927. Serial No. 175,103.

This invention relates to prong receiving contacts.

Objects of this invention are to provide a prong receiving contact for electrical devices which is so constructed that the two lips of the contact are held together permanently in a very rigid and secure manner and independently of the conductor receiving screw or member, so that the conductor receiving member may be adjusted, loosened, or tightened, without in any way affecting the relative positioning of the two contact receiving lips or members.

Further objects are to provide a prong receiving contact which is so constructed that it may be readily formed for its major part from flat sheet metal and easily shaped, and which is so constructed that a rivet is employed for holding the two lips of the device in an intimate contact, such rivet being itself tapped for the reception of the screw and thus performing a double function and acting both as a rigid clamp for the lips of the device and also as a threaded bushing for the reception of the screw.

Further, it is well known that the guiding lips for the wires have been universally formed at the side of the prong receiving member and, consequently, do not accurately 30 guide the wire or conductor, but instead, provide a relatively large space in which the conductor may move with the consequent loosening of the screw.

This invention is designed to overcome the defect noted above and a further object of the invention is to provide a novel form of upturned ears so positioned that a downwardly tapered restricted slot is provided for the reception of the end of the wire adjacent the screw so that the wire is held against motion, and to so construct these ears that they may be formed without requiring additional width of the stock.

Further objects are to provide an upturned rear end for the contact clip which is equipped with the ears for guiding the wire and which also abuts the rear end of the upper clip member and in cooperation with the rivet securely retains the upper member against relative

rocking motion with respect to the lower member.

An embodiment of the invention is shown in the accompanying drawings in which:

Figure 1 is a plan view of the device;

Figure 2 is a sectional view on the line 2—2 of Figure 1;

Figure 3 is a rear view of the device;

Figure 4 is a front view of the device.

Referring to the drawings, it will be seen that the prong receiving contact consists of a lower clip 1 and an upper clip 2 whose flattened portions are held together by means of a rivet 3. These members 1 and 2 are arched laterally into the form shown particularly in Figures 2 and 4, and thus provide partially rounded lips 4 and 5 for the reception of the prong.

The rear end of the flat portion 2 of the upper clip abuts the upturned rear portion 6 of the lower clip and forms therewith a relatively wide contacting or bearing surface which in conjunction with the rivet 3, prevents relative turning of the two portions of the clip. This upturned portion 6 is continued upwardly in the form of a pair of spaced ears 7 which have a gradually constricted space 8 between them with the lower portion of this notch or opening rounded to thus avoid any possibility of cutting of the wires.

It is to be noted particularly that the upturned rear portion of the lower clip is of the same width as the body portion of the clip and, consequently, an increase in the width of stock is avoided with the result that relatively narrow stock can be used in the manufacture of these clips, as distinguished from the relatively wider stock that is necessary for clips having side lugs turned inwardly over the other clip.

It is to be noted particularly that the rivet 3 is provided with a central aperture tapped for the reception of the screw 9 whose relatively large head 10 binds the curved end or looped end 11 of the conductor or wire 12 between itself and the upper flat face of the rivet 3, as shown most clearly in Figure 2. This insures a secure contact between the con-

In testimony that I claim the foregoing I have hereunto set my hand at Manitowoc, in the county of Manitowoc, and State of Wisconsin.

JOSEPH PETER EASTMAN.

76

ductor and the clip and in conjunction with the downwardly tapered notch formed between the ears 7 retains the conductor against loosening due to lateral motion or rocking motion about the screw.

Thus, it will be seen that a prong receiving contact has been provided in which the clips are held together by means independent of the adjustment of the conductor clamping member, but which cooperates with the conductor clamping member to securely clamp the conductor in intimate binding engagement with the contact members.

It will be seen further that the upturned rear portion of the lower clip performs the double function of providing ears for accurately positioning the conductor and also of providing an abrupt shoulder against which the rear end of the upper clip bears, to thus prevent relative turning of the two clips forming the contact member.

Further, attention is directed to the extreme simplicity of construction attained by this invention.

It will be seen that flat stock of uniform width throughout may be employed in the formation of the clip and that the two parts may be securely held together by means of a single rivet which not only binds them together, but in conjunction with the upturned end prevents relative rotation. Further, this rivet forms the threaded bushing for the reception of the clamping screw.

Although the invention has been described in considerable detail, such description is intended as illustrative rather than limiting as the invention may be variously embodied and as the scope of such invention is to be determined as claimed.

I claim:

1. A prong receiving contact comprising a pair of clips, means joining said clips, one of said clips having its rear end upturned and provided with a pair of spaced lugs, the other of said clips having its corresponding end in abutting engagement with the upturned end of said first mentioned clip.

2. A prong receiving contact comprising a pair of clips, a rivet rigidly joining said clips, one of said clips having an offset end provided with a pair of conductor guiding prongs, the other of said clips having an abrupt shoulder abutting said upturned end, said rivet having a tapped hole therethrough, and a conductor clamping screw threaded into the tapped hole of said rivet.

3. A prong receiving contact comprising a pair of clips, a rivet joining said clips, a conductor gripping member co-operating with said rivet to grip a conductor, one of said clips having its rear end upturned and provided with a pair of spaced lugs, the other of said lugs having its corresponding end in abutting engagement with the upturned end of said first clip.
